United States Patent Office.

WILLIAM R. ENGLISH AND JASON McCLURE, OF ENGLISH CENTRE,
PENNSYLVANIA.

Letters Patent No. 96,213, dated October 26, 1869.

IMPROVEMENT IN WAGON-SEATS.

The Schedule referred to in these Letters Patent and making part of the same.

To all whom it may concern:

Be it known that we, WILLIAM R. ENGLISH and JASON McCLURE, of English Centre, in the county of Lycoming, and in the State of Pennsylvania, have invented certain new and useful Improvements in Wagon-Seats; and do hereby declare that the following is a full, clear, and exact description thereof, referring being had to the accompanying drawings, and to the letters of reference marked thereon, making a part of this specification.

The nature of our invention consists in the construction and arrangement of springs for wagon-seats, or other purposes, to which they may be applied.

In order to enable others skilled in the art to which our invention appertains, to make and use the same, we will now proceed to describe its construction and operation, referring to the annexed drawings, in which—

Figure 1 is a front view of a wagon-seat resting on our improved springs, and

Figure 2 is a plan view of the bar that connects two sets of springs under the wagon-seat.

A represents a spring, bent in the centre, its ends extending upward, and are inserted into grooves or recesses in the under side of the seat B.

C is another spring, similar to the spring A, but

inverted, and placed directly under the former, their centres coming in contact, as shown in fig. 1.

On each side of the centres of the springs A and C are inserted wedges D D, which keep the springs immediately on each side of their centres, always at the same distance apart.

The springs A C are held together in any suitable manner, but if two or more sets of such springs are used at one time, we connect them all by means of a bar, E, placed above and another below the centres of the springs, which bars are then connected together by pins or rivets a a.

Having thus fully described our invention, What we claim as new, and desire to secure by Letters Patent, is—

The combination, with the grooved bottom of the seat B, of the upper and lower wood-springs A C, wedges D D, metal cross-pieces E E, and bolts a a, all constructed, arranged, and operating substantially as set forth.

In testimony that we claim the foregoing, we have hereunto set our hands, this 27th day of August, 1869.

W. R. ENGLISH.
JASON McCLURE.
